FIG. 5.

UNITED STATES PATENT OFFICE

2,420,812

TOOTHPICK DISPENSER

Frank A. Brunner, Brooklyn, N. Y.

Substituted for abandoned application Serial No.
387,998, April 11, 1941. This application Feb-
ruary 21, 1944, Serial No. 523,315

3 Claims. (Cl. 312—84)

1

This invention relates to dispensers, and more especially to a mechanical means for purveying, one or two at a time, like objects such as toothpicks from a sanitary enclosure or container. The method of accomplishment is also part of this invention. This application is a substitute for abandoned application 387,998, filed April 11, 1941.

An object of the invention is to provide a simple, foolproof toothpick dispenser which will release and expose to the operator one or two toothpicks each time he performs an operation, such as depressing a finger lever.

Another object is to provide a method of releasing from a container, and transmitting to a point outside thereof, one or two of a like group of objects from a pile of them, and by gravity.

A further object is to provide means in such a device to largely or wholly eliminate jamming of the objects within the container, or the feeding of more than one or two at a time.

All these and other objects, as suggested here below, are attained by the method and means now to be described, and illustrated in the accompanying drawings, in which —

Figure 1 is a vertical sectional and quasi-elevational view showing the operational parts of a preferred embodiment of the invention, taken from one side thereof.

Fig. 2 is a vertical elevational view of the same, taken from the rear thereof, with the back wall of the article container removed.

Fig. 3 is a vertical elevational view of the same, taken from the front thereof, with the front wall of the container removed, and only the lower or operating part shown.

Fig. 4 is a perspective view of the movable feeding plate for releasing to the ejecting drum one or two at a time of the toothpicks, matches, pencils, or like objects to be purveyed.

Fig. 5 is a perspective view of the normally stationary but swingably-releasable plate which supports the movable plate above mentioned.

Like numerals refer to like parts throughout the several views.

This invention consists essentially of a base 10 supporting the side walls 11 and removable top 12 of a container, preferably rectangular and vertically positioned. The container's width is somewhat greater than the length of the purveyed toothpicks, for instance.

The upper portion of the container is devoted to a toothpick hopper, to which the toothpicks 13 are supplied in quantity through the top opening, after removing cover 12. This hopper is formed by a stationary plate 14 and a movable plate 15 supported by the vertical end walls 11 of the container or casing. These plates project toward each other and downwardly in somewhat V-form, and have their ends spaced slightly more

than the greatest width of a toothpick, plate 14 pointing toward plate 15 but stopping short of the end thereof, as shown.

Above plate 15, parallel thereto and of slightly less length, is a load plate 16, also supported on the same vertical container wall as is 15. This serves to carry the load of most of the toothpicks after a recent filling, and prevents more than a few resting on plate 15, as clearly shown, and greatly aids in the unjamming operation of the device continuously.

Plate 14 has securely attached thereto on its under surface near its lower end a guide plate 17, shaped as shown, and directing the toothpicks as released between 14 and 15 to slide down the inclined portion of said plate 17 by gravity to fall off onto a second guide plate 18, slanting downwardly in the opposite direction, and permanently affixed to the casing wall near its upper end. From the end of this plate the toothpicks are fed by gravity to the dispensing drum, as explained below.

Plate 15 is shown in perspective in Fig. 4, which shows the parallel notches or serrations 15a along the upper surface of its lower end to a width somewhat greater than the distance between the lower ends of members 14 and 16. Projecting downwardly from the under surface of plate 15, and through slot 22 of plate 19, is a spring-holding post 20 near the upper edge of plate 15; also, near its lower edge, and projecting through slot 23 of plate 18, is a cam-operated post 21.

Plate 19 is hingedly attached to 19a to the side wall of the container, as shown, and projecting downwardly from its under surface is a long bent pin or wire 24, having its lower end urged to the left by coil spring 25 connecting said end to a pin 26 affixed to stationary member 18. By this means swinging plate 19 is held in its raised position, yet permitted to swing downwardly to increase the hopper opening to relieve any jamming of the toothpicks at that point automatically when needed, as by permitting several of them to pass through abreast when so jammed. The normal position of the lower end of plate 19, when once determined by experiment, is fixed by the adjusting bolt 27 with lock nut, which bolt passes through member 24 as shown, and engages a stationary member, as one edge of nearby member 18. Unscrewing this bolt reduces the hopper opening, and vice versa, the last also in case articles of larger diameter are to be purveyed.

Sliding feed plate 15 overlies and is carried by swinging plate 19, the two slots 22, 23 of the latter being long enough for maximum desired sliding travel of plate 15, whose members 20, 21 project there through. Plate 15 is held in its up position by coil spring 28 connecting hinge 19a with pin 29, which latter has a top face

below plate 19 to prevent substantial separation of the two said plates. Stud screw 20a, Fig. 4, may be screwed into 20 to assemble the plates.

Operating lever 29 is pivoted at 30, and has a finger-operating end 29a projecting from the front of the device. Beyond the pivot rearwardly the lever extends upwardly and then sharply forwardly, to terminate in a cam-surfaced end 29b adjacent to pin 21 carried by plate 15 through 19, as explained above. By pressing down on end 29a, the end 29b engages and pushes to the left and downwardly pin 21 to slide feed plate 15 downwardly to release a toothpick or two onto plate 17, then to 18 and the drum. A coil spring 31 returns member 29a upwardly to its original position, this spring being connected as shown between a casing wall 32 and a lever pin 33, both of which are on the other side of pivot 30 from said member 29a.

Wall 32 is also a support for pivot pin 30, being of flat U-shape with one of its side portions adjacent to a container wall; it also supports a stop 34 for limiting the downward movement of thumb member end 29a. This element is not shown in detail, being obvious to those skilled in the art.

Lever 29 also carries a pawl 35 having a hooked upper end 35a, being pivoted to 29 at 36, below which is a pin 38 to which a coil spring 40 connects with another pin 39 on 29 to keep pawl hook 35a always urged to the right, Fig. 1.

A shaft 41 is rotatably supported in side walls 11 as shown, across the lower front portion of the container, and keyed to it is a ratchet wheel 42 and ejecting drum 43, said ratchet 42 being positioned in a concentric centrally-disposed groove in the drum, as shown, and substantially inside the drum's surface. Grooves 43a, concentric, and spaced near each end, are also cut from the drum, which also has its surface longitudinally-notched as shown in cross section in Fig. 1. Note that the curve of these surface notches is such that when passing member 18 the lower portion of all of said notches is in line with the slant of said member 18. These surface notches are just large enough to hold one or two toothpicks.

Flat springs 44, held at 45, extend up into these grooves 43a, which are somewhat greater in depth than the drum's surface grooves, as clearly shown. Springs 44 extend outwardly through an opening in the front wall of the container as shown, and serve to pick up the toothpicks being carried in the drum's surface grooves, and permit them to slide downwardly and out of the container, where they are deposited on a curved take-off ledge or member 46, to be picked up one at a time by the user. Member 18 has lips 18a extending into the two side grooves 43a and the ratchet groove of the drum, and just free of engagement with said drum.

Member 46 is shown removed from Fig. 3, for purposes of clarity.

The drum shaft is equipped with friction washers (not shown) to promptly stop the drum's rotation when the thumb lever is fully depressed. Note that pawl hook 35a always clears the adjacent ratchet tooth on each up movement.

A flat spring member 47, Fig. 2, pointing oppositely to springs 44, may be used to have its end engage the drum's surface grooves to prevent reverse movement of said drum, though this is not always necessary.

Springs 44, 47 also provide friction to prevent undesirable free drum movement.

In operation the toothpicks are put in at the top to position shown, being kept substantially parallel. User depresses finger lever 29a, which rotates drum 43 one tooth of ratchet 42, while cam 29b pushes 21 to left, Fig. 3, to slide plate 15 left to carry a pick or two past the lower end of plate 14, to drop on 17, then 18, into drum notches, around to 44 to take-off ledge 46, and the user.

It should be noted that in some cases the whole drum mechanism may be dispensed with, since the toothpicks are reliably fed one or two at a time by the sliding plate 15 and attendant parts, and when so released they may be simply permitted to fall by gravity to the container exit, as by extending member 18 to the left, or its equivalent.

Objects such as matches and pencils may be purveyed in similar manner; in fact, the heavier and bulkier the object, the more positive is the operation, without refinements such as required for toothpicks, as disclosed here.

Take-off member 46 is scoop-shaped at its top ends, as shown in Fig. 3. The picks rest upon it in almost point contact, thus providing the greatest degree of sanitation for them, which is a prime purpose of the invention.

Having now described the invention, what is claimed as new and for which Letters Patent of the United States is desired is:

1. In an article dispenser, a container, an inclined stationary plate therein and supported thereby, a second inclined plate forming a V with the first plate and having its lower end spaced therefrom, and hinged along its upper edge to the container wall to swing downwardly away from the stationary plate to release the articles therebetween means to hold up said hinged plate, a pair of vertically-spaced fixed deflecting plates secured in said container below and slanted downwardly in opposite directions to retardingly convey the articles in opposite directions successively, and rotary ejecting means adjacent the lowermost deflecting plate to receive and eject the said articles therefrom.

2. In an article dispenser, a casing, a finger-operated L-shaped lever pivoted thereon, an article-dispensing drum above the lever's lower end, a cam extension to the lever positioned above the drum and movable at right angles to said lower end, and a spring-pressed pawl carried by said lever, both the said extension and the pawl being adapted to actuate article-releasing-and-ejecting means, respectively.

3. The invention as in claim 2, there being an ejecting drum, a ratchet to rotate the drum by action of the pawl, and a slidible plate actuated by the extension for releasing the articles.

FRANK A. BRUNNER.
